UNITED STATES PATENT OFFICE.

ELISHA S. HEATH, OF BALTIMORE, MARYLAND.

DESIGN FOR FIRE-PLACE STOVE.

Specification forming part of Design No. 6,150, dated September 24, 1872.

To all whom it may concern:

Be it known that I, ELISHA S. HEATH, of Baltimore, State of Maryland, have produced a new and original Design for a Fire-Place Stove; and I hereby declare that the following is a full and exact description of the same:

The front of body of the stove is composed of three sections, as marked A A A on photographic illustration, each of which sections has two large and one smaller central oval window for illumination. At the sides of the large windows in each section are representations of flowers bordering the edges of the sections, marked B B B. In the center of each section over the smaller windows are three representations of scroll-work, in the center of

which is foliage. Beneath the smaller windows in each section are representations of scroll-work and leaves, below which is a shell partially covered with leaves. Bordering the shell is scroll-work, from the base of which springs foliage, rising to the base of the large windows. In the lower corners of each section is a representation of scroll-work.

What I claim as my invention is—

A design for a fire-place stove with the combination and ornamentation as above described.

ELISHA S. HEATH.
